UNITED STATES PATENT OFFICE.

CHARLES LINDNER, OF HOCKLEY, TEXAS.

IMPROVEMENT IN SAW-MILLS.

Specification forming part of Letters Patent No. **159,589**, dated February 9, 1875; application filed September 19, 1874.

To all whom it may concern:

Be it known that I, CHARLES LINDNER, of Hockley, in the county of Harris and State of Texas, have invented an Improvement in Saw-Mills, of which the following is a specification:

The invention will first be fully described, and then pointed out in the claim.

Figure 1 is a plan view of my improved gear. Fig. 2 is a sectional elevation taken on the line *x x* of Fig. 1; and Fig. 3 is a detail section taken on the line *y y* of Fig. 1.

Similar letters of reference indicate corresponding parts.

A is the saw-arbor, on which is a cone-wheel, B. C is the shaft for feeding the carriage forward. It has a cone-wheel, D, which is the mate to B. E is the intermediate friction-wheel for transmitting the motion from B to D. It has two bevel-faces, one to bear on each cone-wheel, and it is mounted on a slide, F, arranged in a plane parallel to and midway between the planes, whereat the two cone-wheels run in contact with it, and this slide is geared by a toothed rack, I, with a pinion, G, having a hand-lever, H, by which the intermediate wheel is shifted along the faces of the cone-wheels, to vary the motion. J is the friction-wheel on the shaft C for turning the

wheel K on the shaft, which gears with the carriage. L is the wheel on the saw-arbor, and M is the intermediate wheel for running the carriage back. This wheel is mounted on the lever N, which is pivoted at O to a fixed pivot, so as to have a little end motion, and it is connected at the other end by a link, P, to the lever Q, in which the shaft C is journaled, and which is so pivoted at R, that whenever said lever is shifted to gear the feed, it throws out the running-back gear, and when it is shifted so as to gear the running-back train, it throws out the feed.

I am aware that a shifting-lever, combined with a pitman and toggle, to work the forward and backward driving-pulleys of carriage, has been employed; but

What I claim is—

The combination, with a wheel, M, that gears with a wheel, L, on the saw-shaft, of the lever N, slotted and pivoted on fixed pin O, and the link-connected lever Q that forms a bearing for the shaft C, and is pivoted at R, all substantially as and for the purpose specified.

CHARLES LINDNER.
